LIFTING JACK

Alexis Jackson, Bayside, N. Y., assignor to Vadim
S. Makaroff, New York, N. Y.

Application March 27, 1939, Serial No. 264,326

19 Claims. (Cl. 254—8)

My invention relates to lifting jacks and has particular reference to jacks for lifting automotive vehicles at one end in order to render accessible the under side of such vehicles for repairs, etc. My invention has further reference to pneumatic or air operated jacks.

In an ordinary pneumatic jack of this type the lifting power is furnished by a motor consisting of an air cylinder with a piston, the piston being pivotally connected to a frame or base of the jack, the cylinder being mounted on the lifting arms pivotally connected at the lower ends to the frame, the free ends of the arms being used for raising a vehicle. Such jacks have a disadvantage in that the cylinder must be mounted entirely above the lifting arms as otherwise it will interfere with their lowering to the ground. The high cylinder forms an obstruction for the end extension of a vehicle such as rear bumpers, trunks, etc., so that the jack must be sufficiently long to extend under the axle while the cylinder remains outside the bumper or trunk. It is also necessary to shift the cylinder as far as possible to the rear of the jack, thereby increasing the leverage and making necessary a corresponding increase in the lifting force, i. e., diameter of the cylinder. The high cylinder, moreover, interferes with the work around the lifted end of the vehicle.

My invention has for its object, therefore, to provide a jack in which the air cylinder is placed horizontally so that the jack can be moved under the rear bumper of an automobile. With the horizontal mounting of the cylinder it is possible to increase the stroke of the piston, so that the cylinder can be correspondingly reduced in diameter, still further reducing the height of the jack. The horizontal mounting of the cylinder makes it possible to build the frame of the jack around the cylinder, the latter contributing to the stiffness of the frame so that less metal is needed for the frame with a corresponding reduction in the total weight of the device and its cost.

Another disadvantage of ordinary lifts is that the lifting force remains practically constant while the arm is being raised, although the moment of resistance considerably varies, being the greatest at the start and rapidly decreasing as the arm approaches the vertical position. It becomes necessary therefore to provide an air cylinder of a relative large diameter as determined by the initial torque only. In my improved lift I provide a mechanism whereby the leverage between the cylinder and the lifting arm varies, being the greatest at the start when the moment

of resistance is the greatest, and being reduced at the end when the arm is raised. With this arrangement it becomes possible still further to reduce the diameter of the lifting cylinder. The time required for the lifting operation is also reduced since the movement becomes more rapid as the ratio of the leverage is reduced during the latter part of the lifting operation. The change of the moment of the lifting force is accomplished in my jack by providing cam surfaces on the arms and moving them against stationary rollers in such a manner that the angle of the surfaces varies with the raising of the arm, being the smallest at the start. As a result, the arm represents a lever with a variable position of its middle fulcrum, the lower end of the arms having supporting rollers under the frame of the jack. The arm is therefore directly supported on the rollers, relieving the strain from the rear portion of the frame.

Still another object of my invention is to provide a locking mechanism for the jack in order to retain the arm in the raised position regardless of the air pressure in the cylinder. I also provide an improved manual control mechanism, preferably operated by a pedal, for releasing the locking device simultaneously with the release of air from the cylinder when it is desired to lower the arm.

My invention is more fully described in the accompanying specification and drawing in which—

Fig. 1 is a sectional elevation of my jack showing the arms in the raised position, the lowered position being shown in dotted lines;

Fig. 2 is a top plan view of the same;

Fig. 3 is a rear end view of the same;

My lifting jack consists of an air cylinder 1 mounted on a frame formed of two angle iron beams 2. The front ends of the beams support a shaft 4 with supporting wheels 5 at the ends. Brackets 6 are mounted at the sides of the beams 2 for a transverse shaft 7 having rollers 8 at the ends. The rollers engage inner sides of arms 9 made of channel bars joined together at the middle by a bridge plate 10. The lower ends of the arms are joined by a shaft 11 with wheels 12 at the ends. Tubular rollers 13 are provided on the shaft 11 to facilitate the sliding movement of the shaft under the beams 2. The arms are bent at the middle so that their free ends occupy a low position indicated in dotted lines in Fig. 1 when the arms are lowered. The wheels 12 recede to the rear of the cylinder when the arms are lowered as shown in dotted lines in Fig. 1. The

shaft 12 is also connected by links 14 with the ends of a cross-bar 15 resting on the upper edges of the beams 2, rollers 16 being provided to reduce the friction at the points of contact. The cross-bar 15 is connected at the middle by a bolt 17 to the end of a rod 18 extending from a piston 19 in the cylinder 1. The rod 18 is made of two channel bars welded together at the edges.

A valve nipple 20 is provided for admitting compressed air into the cylinder, the valve being preferably of the type used with automobile tires. A pressure gauge 21 may be provided for indicating air pressure in the cylinders. Sleeves 22 are provided at the sides of the beams 2 for removable handles 23 for moving the jack.

The operation of my jack is as follows:

The front end of the jack is moved under the axle of a vehicle until recessed grippers or forks 24 on the ends of the arms register with the axle. An air hose (not shown) is then fitted on the valve nipple 20 and the air is turned on. As the pressure in the cylinder builds up, the piston will be moved outward, carrying the cross-bar 15 and pulling the links 14. As a result, the shaft 11 will be moved forward, the wheels 12 sliding on the floor. The resistance to this movement is reduced by the provision of the tubular rollers 13 on the shaft 11 and by the fact that the load is supported on the ends of the arms near the front wheels 5 so that a very small fraction of this load rests on the rear wheels 12 before the arms are sufficiently raised. The arms move on the rollers 3, the edges of the channel bars of the arms forming cam surfaces inclined at a small angle to the direction of the pull so that a relatively small force is required to raise the arms. The arms, while sliding over the rollers 3, are also rotated on the shaft 11, the rotation being relatively small at the start. It is gradually increased, however, as the arms are being raised, until at the end the sliding movement almost disappears, being replaced by a simple rotation on the rollers 3. The leverage will be then also reduced, resulting in a more rapid movement of the lifting arm. The torque of the load on the arm will be then correspondingly decreased, however, because of the shortening of the distance between the free ends of the arms and the wheels 3. By properly selecting the relative dimensions of the moving parts it is possible to obtain a practically constant torque for the lifting motor.

A locking mechanism is provided in order to hold the arm in the raised position even if the air should escape from the cylinder. This mechanism comprises a dog 25 keyed on a shaft 26 journaled at the ends in the sides of the brackets 6. The dog slides over the upper side of the rod 18 provided with a series of rectangular holes 27. The dog, when falling in one of the holes, engages the front edge of the hole as shown in Fig. 1, thereby locking the rod and preventing its inward movement under pressure of the load on the arms 9. A fork 28 is also keyed on the shaft 25 and is engaged at the lower end by a compression spring 29 thereby urging the dog against the rod 18. A mechanism is provided for releasing the dog from the piston rod, consisting of a lever 30 pivotally supported on brackets 31 at the rear of the cylinder 1 and having a pedal 32. The end of the lever is connected by a bar 33 with the end of the fork 27, the bar sliding between the shaft 11 and the cylinder 1, the rollers 13 being spaced apart to provide room for the bar 33. The dog 25 is raised by stepping on the pedal 32, thereby turning the lever 30 and moving the fork 28 against

the pressure of the spring 29. An air exhaust valve 34 is fitted in the bottom of the cylinder and connected with the lever 30 in such a manner that the air is released from the cylinder when the pedal is depressed and the dog raised, the arms being then released for their downward movement under the load of a vehicle.

It is understood that my jack may be further modified within the scope of my invention as set forth in the appended claims.

I claim as my invention:

1. A lifting jack comprising a frame, lifting arms, means to slidably and rotatively support the arms on the frame at their intermediate portions, means to support an object on the front ends of the arms, means to slidably support the rear ends of the arms, and means to move the rear ends of the arms forward thereby causing the arms to slide and to rotate on the supporting means at their intermediate portions so as to raise the front ends of the arms.

2. A lifting jack comprising a frame, lifting arms, means to slidably and rotatively support the arms on the frame at their intermediate portions, means to support an object on the front ends of the arms, means to slidably support the rear ends of the arms, and means to move the rear ends of the arms forward thereby causing the arms to slide and to rotate on the supporting means at their intermediate portions so as to raise the front ends of the arms, the arms being bent in the middle so as to bring the front ends below the first-mentioned supporting means when the arms are in the lowered position.

3. A lifting jack comprising a frame, lifting arms, means to slidably and rotatively support the arms on the frame at their intermediate portions, means to support an object on the front ends of the arms, means to slidably support the rear ends of the arms on the ground, and means to move the rear ends of the arms forward thereby causing the arms to slide and rotate on the supporting means at their intermediate portions so as to raise the front ends of the arms.

4. A lifting jack comprising a frame, lifting arms, means to slidably and rotatively support the arms on the frame at their intermediate portions, means to support an object on the front ends of the arms, means to slidably support the rear ends of the arms comprising rollers thereon adapted to slide under the frame, and means to move the rear ends of the arms forward thereby causing the arms to slide and to rotate on the supporting means at their intermediate portions so as to raise the front ends of the arms.

5. A lifting jack comprising a frame, lifting arms, means to slidably and rotatively support the arms on the frame at their intermediate portions, means to support an object on the front ends of the arms, rollers on the rear ends of the arms adapted to slide in engagement with the frame, and means to move the rear ends of the arms forward thereby causing the arms to slide and to rotate on the supporting means at their intermediate portions so as to raise the front ends of the arms.

6. A lifting jack comprising a frame, lifting arms, means to slidably and rotatively support the arms on the frame at their intermediate portions, means to support an object on the front ends of the arms, a shaft connecting the rear ends of the arms passing under the frame, wheels on the shaft for supporting the arms on the ground, rollers on the shaft for supporting the frame on the shaft, and means to move the rear

ends of the arms forward thereby causing the arms to slide and to rotate the supporting means at their intermediate portions so as to raise the front ends of the arms.

7. A lifting jack comprising a frame, lifting arms having cam portions, means to slidably and rotatively support the arms on the frame at their cam portions, means to support an object on the front ends of the arms, means to slidably support the rear ends of the arms on the ground, and means to slidably rotate the arms on their cam supporting means and to move the rear ends forward thereby raising the front ends of the arms.

8. A lifting jack comprising a frame, lifting arms having cam portions, means to slidably and rotatively support the arms on the frame at their cam portions, the supporting means forming fulcrums for the arms, means to support an object on the front ends of the arms, means to slidably support the rear ends of the arms on the ground, and means to rotate the arms on their fulcrums and to cause the rear ends to slidably move forward thereby causing the arms to slide by the cam portions on the fulcrum points so as to raise the front ends of the arms.

9. A lifting jack comprising a frame, wheels supporting the front end of the frame, brackets in the middle of the frame, rollers rotatively supported on the brackets above the frame, lifting arms at the sides of the frame, longitudinal grooves in the arms slidably engaging the rollers, means to rigidly join the two arms together, means on the front ends of the arms for supporting an object, a shaft joining the rear ends of the arms under the frame, wheels on the ends of the shaft for supporting the arms on the ground, means on the shaft supporting the frame, and means to move the shaft with the rollers forward thereby sliding and rotating the arms on the rollers for raising the front ends of the arms.

10. A lifting jack comprising a frame, wheels supporting the front end of the frame, brackets in the middle of the frame, rollers rotatively supported on the brackets above the frame, lifting arms at the sides of the frame made of channel-shaped bars facing each other with their flanges, the flanges slidably engaging the rollers, a member rigidly joining together the arms, means on the front ends of the arms for supporting an object, a shaft joining the rear ends of the arms under the frame, wheels on the ends of the shaft for supporting the arms on the ground, means on the shaft supporting the frame, and means to move the shaft with the rollers forward thereby sliding and rotating the arms on the rollers for raising the front ends of the arms.

11. A lifting jack comprising a frame, lifting arms having cam portions, means to slidably and rotatively support the arms on the frame at their cam portions, the supporting means forming fulcrums for the arms, means to support an object on the front ends of the arms, means to slidably support the rear ends of the arms on the ground, a cross member slidably supported on the front portion of the frame, bars hingedly connecting the rear ends of the arms with the cross member, and means to move the cross member forward thereby moving forward the rear ends of the arms, causing the arms to slide and to rotate on the fulcrums thereby raising the front ends of the arms.

12. A lifting jack comprising a frame, lifting arms having cam portions, means to slidably and rotatively support the arms on the frame at their cam portions, the supporting means forming ful-

crums for the arms, means to support an object on the front ends of the arms, means to slidably support the rear ends of the arms on the ground, a cross member slidably supported on the front portion of the frame, bars hingedly connecting the rear ends of the arms with the cross member, a motor supported on the frame, and means to move the cross bar by the motor, causing the arms to slide and to rotate on the fulcrums thereby raising the front ends of the arms.

13. A lifting jack comprising a frame, lifting arms having cam portions, means to slidably and rotatively support the arms on the frame at their cam portions, the supporting means forming fulcrums for the arms, means to support an object on the front ends of the arms, means to slidably support the rear ends of the arms on the ground, a motor on the frame, and means to rotate the arms on the fulcrums so as to raise the front ends of the arms by the motor while causing the rear ends of the arms to slide on the ground.

14. A lifting jack comprising a frame, a cylinder horizontally mounted on the rear portion of the frame, lifting arms at the sides of the frame, means to rotatively and slidably support the arms at their intermediate portions on the frame, means to support an object on the front ends of the arms, means to slidably support the rear ends of the arms, a piston in the cylinder, a rod on the piston, operative connections between the rod and the rear ends of the arms, and means to admit a fluid under pressure into the cylinder for moving the piston with the rear ends of the arms thereby raising the front ends of the arms.

15. A lifting jack comprising a frame formed of two bars, a cylinder horizontally mounted on the rear portions of the bars and rigidly joining the bars together, lifting arms at the sides of the frame, means to rotatively and slidably support the arms at their intermediate portions on the frame, means to support an object on the front ends of the arms, means to slidably support the rear ends of the arms, a piston in the cylinder, a rod on the piston, operative connections between the rod and the rear ends of the arms, and means to admit a fluid under pressure into the cylinder for moving the piston with the rear ends of the arms thereby raising the front ends of the arms.

16. A lifting jack comprising a frame, a cylinder horizontally mounted on the rear portion of the frame, lifting arms at the sides of the frame, means to rotatively and slidably support the arms at their intermediate portions on the frame, means to support an object on the front ends of the arms, means to slidably support the rear ends of the arms, a piston in the cylinder, a rod on the piston, means to slidably support the front end of the rod on the frame, bars connecting the rod supporting means with the rear ends of the arms, and means to admit a fluid under pressure into the cylinder for moving the piston with the rear ends of the arms thereby raising the front ends of the arms.

17. A lifting jack comprising a frame, a cylinder horizontally mounted on the rear portion of the frame, lifting arms at the sides of the frame, means to rotatively and slidably support the arms at their intermediate portions on the frame, means to support an object on the front ends of the arms, means to slidably support the rear ends of the arms, a piston in the cylinder, a rod on the piston, operative connections between the rod and the rear ends of the arms, means to admit a fluid under pressure into the cylinder for moving the piston with the rear ends of the arms thereby

raising the front ends of the arms, means to lock the rod in the operative position with the arms raised, a pedal at the rear of the frame, and operative connections between the pedal and the locking means for releasing the latter when the pedal is depressed.

18. A lifting jack comprising a frame, a cylinder horizontally mounted on the rear portion of the frame, lifting arms at the sides of the frame, means to rotatively and slidably support the arms at their intermediate portions on the frame, means to support an object on the front ends of the arms, means to slidably support the rear ends of the arms, a piston in the cylinder, a rod on the piston, operative connections between the rod and the rear ends of the arms, means to admit a fluid under pressure into the cylinder for moving the piston with the rear ends of the arms thereby

raising the front ends of the arms, means to lock the rod in the operative position with the arms raised, a pedal at the rear of the frame, operative connections between the pedal and the locking means for releasing the latter when the pedal is depressed, and means to release the fluid from the cylinder when the pedal is depressed.

19. A lifting jack comprising a frame, a lifting member, means to slidably and rotatively support the member at its intermediate portion, means to support an object on the front ends of the lifting member, means to slidably support the rear end of the lifting member, and means to move the rear end of the lifting member, thereby causing the lifting member to slide and to rotate on the supporting means at its intermediate portion so as to raise the front end of the lifting member.

ALEXIS JACKSON.
